UNITED STATES PATENT OFFICE.

AUGUST J. SCHULTZE, OF GALVESTON, TEXAS.

UNIVERSAL LOCK AND LATCH.

1,352,762.

Specification of Letters Patent. Patented Sept. 14, 1920.

Application filed October 31, 1919. Serial No. 334,803.

To all whom it may concern:

Be it known that I, AUGUST J. SCHULTZE, who have obtained my first citizenship papers of the United States, residing at Galveston, in the county of Galveston and States of Texas, have invented certain new and useful Improvements in Universal Locks and Latches; and I do hereby declare the following to be a full, clear, and exact 10 description of the invention, such as will enable others skilled in the art to which it appertains to make and use the same.

This invention relates to locks and latches and is an improvement on my Patent No. 15 1,193,481, issued to me August 1, 1916.

The primary object of the invention is to provide a device embodying a minimum number of parts which can be effectively used, as a gate latch or a door lock and 20 which can be used on either right or left hand swinging doors.

A further object of the invention is to provide an improved lock and latch having an improved means for holding the latching member in locked position in engagement 25 with the keeper and for releasably holding the latch member in active position prior to engaging the keeper.

A further object of the invention is to provide an improved vertically sliding bolt for 30 engaging the latching member for releasably holding the same in active position and for positively holding the same in operative position in engagement with the keeper and 35 an improved means for operating said bolt.

A further object of the invention is to provide an improved means for effectively holding the bolt for the latch against movement when the latch is in operative position in 40 engagement with the keeper, so that the bolt cannot be operated without the use of a key.

A further object of the invention is to provide a manually operated bolt for engaging the latch bolt, so as to hold the latch 45 bolt against movement when the latch member is in operative position.

A still further object of the invention is to provide an improved device of the above character, which is durable and efficient in 50 use, one that is simple and easy to manufacture, and one that can be placed upon the market at a reasonable cost.

With these and other objects in view, the invention consists in the novel construction, arrangement and formation of parts, as will be hereinafter more specifically described, claimed and illustrated in the accompanying drawings, forming a part thereof, in which:

Figure 1 is a front elevation of the improved device. 60

Fig. 2 is a similar view with the cover plate removed.

Fig. 3 is a rear elevation of the device.

Fig. 4 is a detail section taken on the line 4—4 of Fig. 2. 65

Fig. 5 is a similar view showing the latching member in active position.

Fig. 6 is a detail perspective view of the latch member.

Fig. 7 is a detail perspective view of the keeper. 70

Fig. 8 is a front elevation with the cover plate removed, showing a modified form of the invention wherein the same is adapted to be used as a rim door lock. 75

Fig. 9 is a section taken on the line 9—9 of Fig. 8.

Fig. 10 is a detail perspective view of the keeper used in the modified form of the invention, and 80

Fig. 11 is a top plan view of the inner end of the latch member.

Referring to the drawings in detail, wherein similar reference characters designate corresponding parts throughout the several views, the numeral 1 generally indicates the improved device which includes the body 2 carried by the door or gate 3 and the keeper 4 secured to the door frame or gate post 5. 90

The body 2 of the device includes a casing 6 in which is mounted the pivoted latch member 7 and the vertically sliding locking bolt 8. The casing 6 includes an attaching or base plate 9, having a cover plate 10 detachably secured thereto by suitable retaining screws 11 which extend through the cover plate 10 and the base plate 9. Inwardly extending flanges 12 are formed on the edges of the base plate and serve to space the base plate from the door and the upper and lower flanges are provided with outwardly extending attaching flanges 13, which are adapted to receive suitable fasten- 95 100

ing elements 14. Suitable reinforcing webs 15 are carried by the base plate and extend from one flange 12 to the other flange. The forward edge of the base plate is provided 5 with a pair of spaced ears 16 which receive and support the pivot pin 17 on which is rotatably mounted the latch member 7. The base plate 9 is slotted intermediate its ends and between the ears 16, so as to permit free 10 movement of the latch member in relation thereto.

The latch member 7 includes the shank 18 having the vertical bore 19, which receives the pivot pin 17. The forward end of the 15 shank has formed thereon the forwardly projecting substantially U-shaped keeper engaging member 20 and the keeper engaging member is formed relatively long so as to provide an enlarged surface for engaging 20 the keeper. The terminals of the arms 21 of the U-shaped member are flared outwardly and beveled, as at 22, so as to facilitate the engaging of the member 20 with the keeper. The rear end of the shank 18 25 is provided with an inwardly extending arcuate plate 23, the central portion of the upper and lower surface of which is provided with an inwardly extending notch 24 for the reception of the vertically sliding 30 bolt 8, which will hereinafter be more fully described. The upper and lower surfaces of the arcuate member 23 on each side of the slots 24 are provided with inwardly extending notches 25 the inner walls 26 of which 35 are inclined downwardly from the upper surface of the plate toward the outer walls of the notches and the inclined wall 26 provides means whereby the bolt 8 may be slid upwardly during the closing movement of 40 the gate when the U-shaped member 20 rides into engagement with the keeper 4. The inner surfaces of the ears 16 are provided with 45 grooves 27, for the reception of the slide bolt 8 and spaced retaining ears 28 are provided for engaging the side face of the bolt opposite to the face engaged by the ears 16. The lugs 28 and the groove 27 formed in 50 the ears 16 form suitable guideways for the sliding bolt which includes the substantially 55 flat body 29 having the inwardly extending slot 30 which receives the inner edge of the arcuate plate 23. The slot 30 has communicating therewith an upwardly extending slot 35, which in connection with the slot 30 defines a tongue 32 which is adapted to engage 60 in the notches 24 and 25 for retaining the latch member 7 in active and inactive position. The tongue 32 is normally held in engagement with the arcuate plate 23 by means 65 of a leaf spring 33 which engages the outwardly extending feet 34 formed on the terminals of the bolt. The rear edge of the bolt 8 is provided with a pair of spaced ears 31, between which is positioned the cylindrical head 36 of the operating lever 37 which

is rotatably mounted on the pin 38 carried by the base plate 9. The cover plate 6 is also provided with inwardly extending apertured lug 39 which receives the free end of the pin 38, which serves to hold the cover 70 plate against displacement. The outer end of the operating lever 37 is bent upwardly to provide an operating handle 40 by means of which the lever is readily manipulated. It can be seen that by throwing the lever 75 downward, the bolt 8 will be raised and the tongue 32 lifted out of engagement with the notches and above the surface of the plate 23 and permit the latch 7 to readily swing on the pivot pin 17 and thus permit the gate 80 or door to be opened. The base plate 9 is also provided with a transversely extending guideway 41, in which is slidably mounted a locking bolt 42, which is adapted to engage in a notch 43 formed on the inner edge of 85 the bolt 8. The locking bolt 42 forms means for retaining the bolt 8 in its lowered position so as to positively hold the bolt against movement and the latching member in its locked position. The cover plate is provided 90 with a keyhole slot 44 and the guideway is slotted as at 45 so that a key may be readily inserted in the casing so as to engage the locking bolt 42 which is provided with a notch 45' for reception of the key. It can 95 be seen that when the key is placed in the key slot 44 in the casing and turned the bolt will either be brought into or out of engagement with the bolt 8, as desired. The notch 43 is formed adjacent the lower end of the 100 bolt 8 and a similar notch 46 is provided adjacent the upper end of the bolt, for a purpose which will hereinafter more fully appear.

The inner face of the cover plate is also 105 provided with vertically extending ribs 47 which are adapted to engage the outer face of the bolt 8, so as to form means for holding the same in operative position in the guideways. The base plate is also provided 110 with suitable corner lugs 48, which are engaged by the corners of the cover plate, so as to hold the same in position.

The keeper 4 includes the base or attaching plate 49 which is provided with suitable 115 openings 50 for the reception of the fastening elements 51. A horizontally disposed outwardly extending bracket 52 is formed on the plate and extends outwardly toward the inner edge of the base plate and the free 120 end of the bracket supports the cylindrical arm 53 which is adapted to be received between the arms 21 of the U-shaped member 20.

In operation of the improved device, the 125 bolt 42 is retracted and the operating lever 40 swung downwardly which permits the latch to be swung on its pivot and the gate or door opened. Upon releasing of the lever 37 the bolt 8 will be thrown downward by 130

the spring 33 and the tongue 32 forced into engagement with the notch 25, which releasably holds the latch member 7 in its active position. When the gate is drawn 5 closed, the U-shaped member 20 will receive the cylindrical arm 53 which will swing the latch member 7 on its pivot and raise the bolt 8 upward owing to the inclined wall 26. When the latch 7 has reached its central 10 position, the bolt 8 will drop and the tongue 32 will engage in the notch 24 and hold the latch member in its locked position against movement. The locking bolt then may or may not be thrown into engagement 15 with the bolt 8 for holding the same against movement.

The latch as shown is adapted to be used on a left hand swinging door, and when the latch is to be used on a right hand swinging 20 door, the casing is reversed and the bolt 8 and lever 37 likewise reversed so that the tongue 32 will normally tend to gravitate into engagement with the notches 24 and 25.

In Figs. 8 to 10 there has been illustrated 25 a form of the latch which is specially adapted to be used with a rim door lock and this construction is identical with the form illustrated in Figs. 1 to 8 with the exception that the casing is formed of lighter and 30 thinner material and that means is provided whereby the bolt 8 may be operated from either the inside or outside of the door and that a hand operated bolt is provided for engaging the bolt 8 so as to hold the same 35 against movement and the hand operated bolt is so positioned that the same can only be operated from the inside of the door.

The cover plate 6 and the base plate 9 are provided with aligned openings 55 in 40 this form which rotatably receives the sleeve 56 having the squared bore 57 which receives the spindle 58 having the operating knobs 59 formed thereon for permitting the ready turning of the sleeve. The sleeve 56 has 45 also formed thereon the outwardly extending arm 60 which carries the cylindrical lug 61, which is fitted between the ears 31 on the latch bolt 8. The spindle 58 is continued through the door as is usual in the ordinary 50 construction of rim door lock. A second guideway 62 is carried by the base plate 9 adjacent to the upper end thereof and the guideway slidably receives the hand operated bolt 63, which is adapted to engage in 55 the upper notch 46 formed in the latch bolt 8. The hand operated bolt 63 is provided with a reduced stem 63^a which extends through the rear wall of the casing and is provided with a knob 64 for permitting the 60 ready operation of the same.

In this form a keeper 65 is provided which includes the angularly related plates 66 and 67 which are adapted to be secured by means of fastening elements 69 to the corner of the 65 door frame and the outer plate 67 carries

the forwardly extending ears 70 between which is positioned the cylindrical rod 71 which is adapted to be received by the latch member 7. This form of lock and latch is operated identical with the construction 70 illustrated in Figs. 1 to 7 and when it is desired to raise the bolt 8, it is merely necessary to turn one of the knobs 59.

In practice, I have found that the form of my invention illustrated in the accompanying drawings and referred to in the above description, as the preferred embodiment, is the most efficient and practical; yet realizing the conditions concurrent with the adoption of my device will necessarily vary, 80 I desire to emphasize that various minor changes in details of construction, proportion and arrangement of parts may be resorted to, when required without sacrificing any of the advantages of my invention as 85 set forth.

What I claim as new is:

1. In a lock, a base plate, a latch member pivoted on the base plate, a supported keeper to be engaged by the latch member, an extension carried by the pivoted end of the latch member and provided with recesses in its upper face, one of the side walls of one of the recesses being inclined upwardly, a longitudinally movable member mounted on 95 the base plate and adapted to engage in the recess provided with the inclined wall to retain the latch member in a position to move into engagement with the keeper, the longitudinally movable member being lifted 100 out of said notch upon being engaged by the inclined wall upon the pivotal movement of the latch member, and engaging the other notch to retain its latch member in locked engagement with the keeper. 105

2. In a lock, a base plate, a latch member pivotally mounted on the base plate, a keeper to be engaged by the latch member, and an extension carried by the pivoted end of the latch member, and provided with 110 notches in its upper face, a longitudinally movable tumbler mounted on the base plate and provided with an opening intermediate its end to permit the extension to swing therethrough upon pivotal movement of the 115 latch member, and a tongue disposed to one side of the opening and adapted to engage in either of the recesses in the extension to retain the latch member in a position to engage the keeper or to retain the latch member in parallel relation to the base plate in locked engagement with the keeper. 120

3. A lock including a casing, a latch pivoted in the casing and projecting therefrom, an extension carried by the pivoted 125 end of the latch and having a plurality of spaced recesses therein, a tumbler slidably mounted in the casing and movable at right angles to the path of movement of the latch, the tumbler being provided with an open- 130

ing at one side through which the extension is adapted to pass, the forming of such opening affording a tongue engageable in any of the recesses to lock the latch in various positions, and a bolt slidable at right to the tumbler to engage the latter to retain the same in locked engagement with the extension.

In testimony whereof I affix my signature in presence of two witnesses.

AUGUST J. SCHULTZE.
